attorney.

UNITED STATES PATENT OFFICE.

CHARLES A. ECK, OF NEWARK, NEW JERSEY.

DYNAMO-ELECTRIC MACHINE.

SPECIFICATION forming part of Letters Patent No. 633,641, dated September 26, 1899.

Application filed July 28, 1899. Serial No. 725,355. (No model.)

To all whom it may concern:

Be it known that I, CHARLES A. ECK, a subject of the King of Sweden and Norway, residing at Newark, in the county of Essex and 5 State of New Jersey, have invented certain new and useful Improvements in Dynamo-Electric Machines, of which the following is a specification.

My invention relates generally to improvements in dynamo-electric machines and particularly to the adaptation of the brush-holders and adjacent parts of same to the construction of the frame or yoke shown and described in Patent No. 627,488, granted to me 10

June 27, 1899.

To this end the invention consists in the improved brush-holders, the configurative adaptation of the brushes to same, and, broadly speaking, in the combination of co-operative 20 elements contiguous to said brush-holders, as will be fully set forth farther on in the specification.

Several objections may be urged against the type of brush-holders now commonly used— 25 such as, for instance, the comparative inaccessibility of the brushes when they are worn and it is desired to replace them, the inability to inspect the working parts of the brush-holders without a laborious dismantling of 30 part of the machine, and other awkward features of a like nature, all tending to reduce the efficiency of the motor. It has accordingly been the object of my invention to obviate these and similar disadvantages—in short, 35 to provide a brush-holder so constructed and so arranged with regard to the surrounding parts of the machine as to be efficient in operation, cheap in construction, and easy of access in all respects. Although changes may 40 be made without departing from the spirit of my invention, I believe these objects to be best attained by the construction shown in the accompanying drawings, in which—

Figure 1 is a rear view of my improved dynamo-electric machine, showing the brush-holders with their brushes in position, the means used for securing said brush-holders to the motor, and the method of securing them (the brush-holders) rigidly together. 45 Fig. 2 is a detail view of one of the brush-holders, showing also insulating-disk and screw-insulator. Fig. 3 is a second view of

one of the brush-holders, looking at it from above and at right angles to the position shown in Fig. 2, the brush being removed. Fig. 4 is 55 a sectional view of one of the brush-holders, taken on line x - x of Fig. 3. Fig. 5 is a detail view of a combined insulating brush-holder bracket and armature-shield. Fig. 6 is a detail view of an insulating-disk. Fig. 7 is an 60 end view of one of the brushes, showing its cross-sectional outline.

Similar letters and numerals of reference indicate corresponding parts in the different views. 65

I shall describe a dynamo-electric machine embodying my invention and afterward point out the novel features in the claims.

1 indicates a yoke or frame. 2 is a central hole in the wall of same, serving both as a 70 shaft-hole for the shaft of the armature and commutator and also, owing to its peculiarly elongated form, as a means of introducing the field-coils into the yoke.

3 is the armature-shaft, supported in the 75 bearing 4 by suitable means, a similar bearing being located on the opposite side of the frame to support the other end of the armature-shaft. These bearings may be of any desired construction suitable for the purpose; 80 but each bearing consists, preferably, of a journal 4^a, having four radially-disposed L-shaped arms arranged with regard to each other in an upper and a lower pair 4^b and 4^c, respectively, each of which two pairs of arms terminates in a fastening-plate 4^d, which is screwed onto the frame. Lubricating means, such as an oil-cup 5, is furnished for lubricating the bearing. 85

6 is the commutator, and 7 is a combined insulating brush-holder bracket and armature-shield. This bracket or shield is formed in the shape of a flat ring with two horizontally-extended arms and is provided with six holes, as shown—three on each side of the central 95 hole—the function of which will become apparent later on.

8 are two interchangeable brush-holders, each having a fastening-piece 12 extending at an angle from the main body, with holes 100 for the admission of screw-insulators 13. By means of these fastening-pieces and screws the brush-holders are fastened to the frame. An insulating-disk 27 is interposed between

the fastening-pieces of the brush-holders and the frame, and this, together with the screw-insulators, forms a perfect insulation. Each of these brush-holders is further provided with two projections 8^a, having screw-cut holes, by means of the corresponding screws of which the brush-holders are fastened on the combined insulating brush-holder bracket and armature-shield, thus securing a rigid connection between said brush-holders. The portion 21, forming the bridge between the brush-holder and the fastening-piece of same, is furnished with a transverse hole 22 for the admission of the leading-out wires. (Not shown.) A second hole 23 is drilled at right angles to the first hole and is for the admission of a tightening-screw 24 to hold the wires in position. The wires are passed from the inside of the frame through the hole *w*, located at each end of the bracket or shield 7, and are then secured in the hole 22 in each of the brush-holders, as before mentioned. It will thus be seen that this bracket or shield 7 serves, first, as an insulating-bracket for holding the brush-holders, and, secondly, as a shield for preventing to a degree the admission of dust and impurities inside the frame of the motor, and consequently to the armature of same.

9 is the brush. The brush-holder is composed of an upper compartment 10 for holding the brush and a lower compartment 11, in which a spring-actuated plunger 12^c works. The lower compartment 11 consists of a sleeve 35 closed at one end and open at the other. Of this sleeve the portion 14, which serves as a wall between the upper and lower compartments, has a longitudinal slot 18, which extends a short distance beyond the point at 40 which the upper compartment ends. A cut-out 18^a, located at right angles to the slot 18 and communicating with same, is provided in the sleeve at the point where the slot 18 terminates. The upper compartment 10 is 45 simply formed of two walls 16, rising from the upper surface of the sleeve 11. These walls are provided with ledges 17 at their upper edges, and one of the walls is further provided with a slot 10^a, permitting the admission of a collector-spring 19, retained between the wall and the projection 20, as shown. The lower compartment or sleeve 11 contains 50 at its closed end the spring 25, which is confined there by the plunger 12^c. This plunger is in the form of a small cylindrical piece 12^a of the same diameter as the sleeve, or very nearly so, and has a pin 12^b inserted, whose axis is at right angles to the axis of the piece 12^a. 55 When for some reason or other a brush is removed from its brush-holder after having been somewhat worn, it oftentimes happens that when it is inserted again it is turned upside down and worn the other way. In such cases a sharp point or apex will be formed on the brush which will cut into the mica strips

of the commutator and tend to destroy the same. To obviate this, my brush is formed with a cross-sectional outline as shown in Fig. 7, where it will be noticed one side is 70 shown as being slightly curved or raised in the middle, the purpose of this being always to present the brush in the same way to the commutator, as it is impossible to insert the former into the brush-holder when turned upside down on account of the two ledges 17, formed at the top of the walls of the upper compartment 10. When it is desired to insert a brush into the brush-holder, the plunger is carried back by means of the 80 finger and given a turn, so as to make the pin rest in the cut-out 18^a, where it is retained, as shown in Fig. 3. The brush is now inserted from the rear, pushing the collector-spring aside as it travels along. The plunger is then turned so as to bring the pin out of the cut-out 18^a and into line with the slot 18, thereby releasing it from its locked position, and the plunger actuated by the spring will be pushed forward until it encounters 90 the brush, which latter it will bring to bear against the commutator with a constant pressure. When it is desired to remove the brush, the plunger is simply brought back and turned into its locked position, when the 95 brush can be slid out without any difficulty.

As the armature-shaft rotates at a high rate of speed, it has a tendency to impart a vibrating movement to the brushes, causing the latter to rattle in a disagreeable way. 100 This difficulty I have overcome by the aid of the collector-spring, which takes up this vibrating motion and prevents the rattling noise. It will be noticed that owing to the direction of the motion of the armature-shaft, 105 which is in the direction of the arrow-head, the collector-spring is located at the lower side and upper side of the brush-holders, respectively, on the right and left hand side of the machine, looking at it from the back. 110

It sometimes occurs that a layer of dust is formed between the brush-holder and the brush, causing thereby the circuit to be impaired. This is also obviated by the collector-spring, inasmuch as owing to the constant 115 friction occasioned by the taking up of the motion of the brush by the collector-spring there will always be a clean surface free from dust and the circuit will remain unimpaired.

It will thus be seen that my improvements 120 combine simplicity of construction with a very high efficiency and that they tend in all ways to increase the facility with which the brush-holders and surrounding parts can be inspected and repaired when occasion requires it; also, that they decrease to a very great extent the disagreeable features occasioned by the clumsy mechanical constructions hitherto employed in this art. 125

Having thus described my invention, what 130 I claim is—

1. A brush-holder having two superposed

compartments extending parallel to each other and a fastening-piece extending at an angle to the said compartments, substantially as described.

5 2. In a brush-holder having two superposed compartments extending parallel to each other, the combination with the portion forming the wall between said compartments of a slot, and a cut-out extending at right angles 10 to the axis of said slot, substantially as described.

3. In a brush-holder having two superposed compartments extending parallel to each other and of the character set forth, the combination with the lower compartment of a 15 spring-actuated plunger, substantially as described.

4. In a brush-holder of the character set forth, a lower compartment consisting of a 20 sleeve closed at one end, an upper compartment consisting of two walls formed on the upper side of the lower compartment, each wall having a ledge on its upper edge, said upper compartment having both ends open, 25 and a collector-spring inserted in one of the walls, a longitudinal slot formed in the wall separating the two compartments, a cut-out communicating with such slot and a spring-actuated plunger of the character set forth 30 substantially as described.

5. The combination in a brush-holder of the character set forth of an upper compartment for holding a brush, a lower compartment, a spring-actuated plunger operating in 35 the lower compartment, and upon the brush in the upper compartment, a fastening-piece extending at an angle to the two compartments, means formed between the lower compartment and the fastening-piece for holding 40 the leading-out wires, substantially as described.

6. In a brush-holder having two superposed compartments extending parallel to each other, means formed in one of said compartments for taking up the vibration of the brush contained in said compartment, substantially 45 as described.

7. In a brush-holder having two superposed compartments extending parallel to each other, a spring-actuated plunger operating in 50 one of said compartments and means for lock-

ing said plunger when not in use, substantially as described.

8. In a brush-holder having two superposed compartments extending parallel to each other, the combination with the two walls forming the upper compartment of two ledges, located at the upper edge of said walls for the purposes as set forth, substantially as described. 55 60

9. In a brush-holder having two superposed compartments extending parallel to each other, the combination with one of the walls forming the upper compartment of a slot, a collector-spring for the purposes as set forth, 65 and a projection formed on the outside of said wall for holding the collector-spring, substantially as described.

10. In a brush-holder having two superposed compartments extending parallel to each other, the combination with the wall separating the two compartments of a longitudinal slot and a cut-out extending at right angles to the axis of the longitudinal slot and communicating with same at the point where 75 the latter terminates, substantially as described. 70

11. In a dynamo-electric machine the combination with a brush having one side curved in cross-section of one of two superposed compartments of a brush-holder, and means formed in said compartment for preventing the insertion of the brush wrong side up, substantially as described. 80

12. In a dynamo-electric machine, a brush 85 having one curved and three straight surfaces in cross-sectional outline, for the purposes as set forth, substantially as described.

13. In an insulating brush-holder bracket and armature-shield of a dynamo-electric machine, a flat circular portion with two arms extended from said circular portion, a central shaft-hole, holes for the admission of screws and holes for the admission of the leading-out wires, substantially as described. 90 95

In testimony that I claim the foregoing I have hereunto set my hand this 19th day of July, 1899.

CHARLES A. ECK.
